REINFORCED BUILDING PAPER

Thomas J. Fraber, Washington, D. C.

Application August 3, 1936, Serial No. 94,073

3 Claims. (Cl. 72—116)

This invention relates to building construction and has special reference to reinforced building paper.

One important object of the invention is to provide a novel form of reinforcement for building paper peculiarly adapted to hold plaster applied to the building paper, the reinforcement being so arranged that the plaster will key thereto.

A second important object of the invention is to provide a novel building paper reinforcement constructed of thin metal strips.

A third important object of the invention is to provide a novel arrangement of building paper and reinforcement wherein the building paper and reinforcement are secured together in a novel and improved manner.

With the above and other objects in view, the invention consists in general of certain novel details of construction and combinations of parts hereinafter fully described, illustrated in the accompanying drawing and particularly pointed out in the claims.

In the accompanying drawing like characters of reference indicate like parts in the several views 25 and:—

Fig. 1 is a face view of one unit or sheet of building paper and reinforcement constructed in accordance with this invention.

Fig. 2 is a bottom edge view of the sheet shown 30 in Fig. 1.

Fig. 3 is a magnified detail section on the line 3—3 of Fig. 1.

Fig. 4 is a similar section on the line 4—4 of Fig. 1.

In the embodiment of the invention here illustrated there is shown a sheet 10 of building paper which is supplied with vertical reinforcing members indicated in general at 11 and horizontal reinforcing members indicated in general at 12.

As here shown but two vertical and two horizontal reinforcing members are shown but it is to be understood that as many vertical and as many horizontal members may be used as is found convenient to reinforce whatever sized sheet of building paper is adopted. The principles of the invention are, however, clearly shown in the present disclosure.

Each of the members 11 consists of a strip of thin metal trough shaped in cross-section and having a flat bottom 13 and flat outwardly flaring sides 14. At intervals along the bottom 13 slits of inverted substantially U-shape are formed to provide tongues 15 integral at their lower ends with the bottom 13. These tongues are bent up 50 with the bottom 13. These tongues are bent up and over the transverse members 12 which lie on

the edges of the trough sides 14. The ends of the tongues 15 are bent down as at 16 to hold the members 12 in place.

Each of the members 12 is formed from a strip of thin metal having spaced arch portions 17 which are connected by flat portions 18. The portions 18 lie in the plane of the trough bottoms 13 and the trough bottoms and these portions lie flat on the sheet of building paper. V-shaped slits 19 are spaced along the portions 18 and trough bottoms 13 to form pointed prongs 20 which pass through the building paper and are flattened thereagainst to lock the paper and reinforcement together.

In use the sheets are secured to the studding, 15 rafters or the like building elements by staples straddling the members 11, nails driven through these members or in other desired manner. When thus secured plaster applied to the reinforced face of the device will key under the 20 trough sides 14 and the end portions of the arches 17 so that it is firmly held in place.

There has thus been provided a simple and efficient device of the kind described and for the purpose specified.

Changes may be made in the proportions and details of the invention so that the invention is not restricted to the exact form here shown and described but includes all forms which come with the scope of the appended claims.

What is claimed, is:—

1. In a reinforced building paper sheet, reinforcing means comprising spaced vertical strips of their metal provided with upwardly extending tongues and paper holding prongs, and spaced horizontal thin metal strips crossing said vertical strips and secured thereto by said vertical tongues, said horizontal strips being provided with spaced paper holding prongs extending from the strips in a direction opposite the said tongues.

2. In a reinforced building paper sheet, reinforcing means comprising spaced vertical strips of their metal provided with upwardly extending tongues and paper holding prongs, and spaced horizontal thin metal strips crossing said vertical strips and secured thereto by said tongues, said horizontal strips being provided with spaced paper holding prongs, said vertical strips being trough shaped in cross-section with the sides of the trough flaring outwardly from a flat bottom and the horizontal strips being arched over the vertical strips and having the portions intermediate the arched portions in the plane of the trough bottoms.

3. In a reinforced building paper sheet, a series

of vertical strips of thin sheet metal, a series of horizontal strips of thin sheet metal, the vertical and horizontal strips having flat portions located in the same plane, the horizontal strips having 5 arched portions crossing the vertical strips, prongs projecting from the vertical strips and engaging over the horizontal strips, and other

prongs projecting from the vertical and horizontal strips in a direction opposite the vertical strips, a building paper held by the last prongs against the strips in the plane of the flat portions thereof.

THOMAS J. FRABER.
